(57) **CLAIM**

The ornamental design for a trim positioning tool, as shown and described.

DESCRIPTION

FIG. 1 is a top view of one embodiment according to the present trim positioning tool;

FIG. 2 is a bottom view thereof;

FIG. 3 is a front view thereof;

FIG. 4 is a rear view thereof;

FIG. 5 is a right side view thereof;

FIG. 6 is a left side view thereof;

FIG. 7 is a top front perspective view thereof;

FIG. 8 is a bottom rear perspective view thereof;

FIG. 9 is a left rear perspective view thereof shown in a position of use; and

FIG. 10 is another left rear perspective view thereof shown in a position of use.

FIG. 11 is a top view of one embodiment according to the present trim positioning tool;

FIG. 12 is a bottom view thereof;

FIG. 13 is a front view thereof;

FIG. 14 is a rear view thereof;

FIG. 15 is a right side view thereof;

FIG. 16 is a left side view thereof;

FIG. 17 is a left rear perspective view thereof;

FIG. 18 is a bottom front perspective view thereof;

FIG. 19 is a top perspective view thereof shown in a position of use; and,

FIG. 20 is a top front perspective view thereof shown in a position of use.

The broken lines represent portions of the article, and form no part of the claimed design. Additional broken lines in FIGS. 9, 10, 19, and 20, are directed to environment and form no part of the claimed design.

1 Claim, 8 Drawing Sheets
